Primary Examiner — Daniel J Domino*Assistant Examiner* — Lee D. Starr(57) **CLAIM**

The ornamental design for a LED light therapy mask, as shown and described.

DESCRIPTION

FIG. 1 is a top, front and right perspective view of a LED light therapy mask showing my new design;

FIG. 2 is a bottom, rear and left perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof;

FIG. 8 is a bottom plan view thereof; and,

FIG. 9 is an enlarged view of a portion labeled as 9 on FIG. 2.

The dashed broken lines illustrate portions of the LED light therapy mask that form no part of the claimed design. The dash-dot broken lines in FIGS. 2 and 9 depict the bounds of the enlargement and form no part of the claimed design.
